UNITED STATES PATENT OFFICE.

DONALD MCKAY, OF MONTGOMERY, ALABAMA.

DUST-CAP FOR VEHICLE-WHEELS.

1,091,072.

Specification of Letters Patent. Patented Mar. 24, 1914.

Application filed June 19, 1913. Serial No. 774,665.

To all whom it may concern:

Be it known that I, DONALD MCKAY, a citizen of the United States, residing at Montgomery, in the county of Montgomery and State of Alabama, have invented a new and useful Dust-Cap for Vehicle-Wheels, of which the following is a specification.

This invention relates to vehicle wheels and more particularly to means whereby the admission of dust to the bearing is prevented.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawings the preferred form of the invention has been shown.

25 In said drawings: Figure 1 is a side elevation of a wheel hub having the present improvements combined therewith. Fig. 2 is a section on line A—B Fig. 1. Fig. 3 is a section on line E—F Fig. 2.

30 Referring to the figures by characters of reference 1 designates an axle having a spindle 2, this spindle being adapted to project into the hub 10 of a wheel having a suitable bearing 7.

35 The inner portion of the hub 10 is surrounded by a dust cap made up of upper and lower sections 17 and 18 respectively, each section being substantially semi-circular in cross section, the upper section 17 being slightly larger than the lower section 18 so that its side edges and its inner end will lap the corresponding edges and end of the lower section 18. These sections are

adapted to fit close to the hub 10 and the inner or closed ends of the sections have interfitting oppositely disposed trough-like extensions 19 and 20 respectively, the section 19 being formed integral with the cap section 17 while the section 20 is formed integral with the cap section 18. The section 19 is adapted to lap the outer faces of the section 20. Any suitable means, such as a clip 21 can be employed for binding the sections 19 and 20 upon the axle 1. A dust guard 22, which is circular in cross section, 45 is secured to the inner end portions of the spokes of the wheel and is extended close to the cap 17—18 so as to prevent dust from working between the free edge of the cap and the hub 10. 50

It will be seen that by providing the particular form of dust cap, the admission of dust and moisture to the bearing is practically prevented.

What is claimed is:—

The combination with an axle, of a hub adapted to rotate thereon, a dust cap extending around the inner portion of the hub and including upper and lower interfitting sections, said upper section lapping the outer sides of the lower section, there being upper and lower trough-like extensions upon the upper and lower sections respectively and embracing the axle, means for binding the extensions upon the axle, and a shield secured to the hub and extending around that end portion of the dust cap nearest the hub. 70

In testimony that I claim the foregoing as my own, I have hereto affixed my signature in the presence of two witnesses.

DONALD MCKAY.
